METHOD OF AND APPARATUS FOR RECORDING AND REPRODUCING ELECTRICAL IMPULSES

Original Filed Dec. 20, 1928

INVENTOR
ROBERT E. RUTHERFORD
BY Charles S. Evans
HIS ATTORNEY.

UNITED STATES PATENT OFFICE

ROBERT E. RUTHERFORD, OF PHILADELPHIA, PENNSYLVANIA

METHOD OF AND APPARATUS FOR RECORDING AND REPRODUCING ELECTRICAL IMPULSES

Application filed December 20, 1928, Serial No. 327,333. Renewed July 29, 1932.

My invention relates to the recording of electrical impulses, and particularly to the electrical recording of sound.

An object of my invention is to provide 5 a new and simple method of sound recordation.

Another object of my invention is to provide a means of recording any succession of 10 electrical impulses, as for example telegraph or television signals.

Still another object of my invention is to provide a method of recording sounds, which is substantially free from effects producing subsidiary or interferent noises.

15 A further object of my invention is to provide an inexpensive and practically permanent sound record.

My invention possesses other objects and 20 valuable features, some of which will be set forth in the following description of my invention which is illustrated in the drawing forming part of the specification. It is to be understood that I do not limit myself to the showing made by the said description 25 and drawing, as I may adopt varying forms of my invention within the scope of the claims.

Referring to the drawing:

Figure 1 is a plan view of an electrical 30 recorder and reproducer embodying my invention.

Figure 2 is a longitudinal sectional view 35 of the apparatus shown in Figure 1, the plane of section being on the line 2—2 of Fig. 1. The electrical circuits used in recording and reproducing sound are diagrammatically shown in this figure.

Considered broadly, my invention 40 comprises the recording of electrical impulses by electrizing a dielectric, and their reproduction by affecting an electrostatically sensitive relay by the electrized dielectric.

Electrostatic charges are usually of a temporary character and dissipate themselves or 45 are discharged within a short time. It has been known for some years, however, that it is possible to produce permanent electrical charges upon certain dielectrics, and for this 50 process the term "electrization" has been pro-

posed and has come to be generally accepted as meaning a permanent electrification.

While electrization of some dielectrics may be produced by bombardment with cathode rays, the more convenient method 55 is to allow a liquid or molten dielectric to solidify in an electrostatic field. Most dielectrics are better conductors in a liquid than in a solid state, and it appears probable that ions are formed in the liquid dielectric which cannot recombine and neutralize their charges when the material solidifies. This phenomenon has been observed in such dielectrics as beeswax, resins, carnauba wax, shellac, paraffin, and various mixtures 60 of these and other ingredients. Whatever the mechanics of the effect may be, it is known that the electrization remains sensibly constant for periods of several years, or as long as the effects have been under observation. 70 These effects are utilized in my method of electrical recording.

In the form of my invention which I have chosen for detailed description, the impulses to be recorded are sound waves translated 75 into electrical impulses by the microphone 1 which feeds into a speech amplifier 2. The entire recording apparatus is mounted on a grounded metal base 6. The record is formed on a paper strip or tape 7, which is impregnated with a dielectric such as paraffin having a suitable melting point, i. e., one higher than the ambient temperatures to which it may be subjected but not so high as to injure the paper. In making the record the tape is 80 transferred from a feed reel 8 to a receiving reel 9, the reels being journaled respectively 85 on the standards 11 and 12 mounted on opposite ends of the base 6.

The tape is drawn thru the apparatus by a 90 pair of rubber covered rollers 13 and 14, which are fixed to the shafts 16 and 17, journaled in the bracket 18. A pulley 19 on the shaft 16 is geared to the motor 21 by the belt 22 and drive pulley 23. A smaller pulley 24, 95 fixed to the shaft 17, drives the receiving reel 9 by means of the slip-belt 26 and pulley 27 on the reel shaft 28. The speed of the tape is thus determined by the roller 14, but the tape 100 is constantly kept taut by the reel 9, whose

tendency to over-run is compensated for by the slipping of the belt 26.

Adjacent the feed reel 8 the tape runs under a guide wheel 31 and thence over an electrical heating element 32 mounted on a bracket 33 secured to the base. Closely adjacent the heating element is a hollow platen 34 supplied with inlet and outlet pipes 36 and 37 thru which water or cold brine may be circulated. It will thus be seen that as the tape is run thru the machine, the dielectric is melted by the heater and then quickly chilled by the cooling platen.

Mounted above the platen on the insulating pillars 38 is a conducting plate 39, spaced above the platen just sufficiently to allow the easy passage of the tape therebetween. This plate is connected to the plate circuit of the output tube of the speech amplifier 2, which is actuated by the electrical impulses to be recorded. A strong variable electrostatic field is therefore established between the plate and the platen, which is grounded to the base and hence connected to the grounded side of the amplifier output circuit.

It will be seen that as the tape is rapidly and uniformly drawn thru the apparatus, there is a fixed position or narrow line determined by the critical temperature of the dielectric within the field at which solidification and electrization of the dielectric occurs. The field at this position changes with the incoming electrical impulses, and the successive elementary areas of the dielectric are differentially electrified in correspondence with the successive impulses. The use of a fairly wide conductor plate and platen maintains the line of solidification in the electrostatic field during minor temperature variations.

The fixed charges due to the electrization have a maximum value of the same order of magnitude as the maximum temporary charges which can be produced by friction. The formation of such temporary charges can be largely suppressed and anomalous results prevented by metallizing the grounded surface 41 of the paper strip or otherwise rendering it conducting. This appears to have an additional advantage in rendering the electrization more permanent, but altho it is a desirable expedient, it is not an essential one.

The reproducing equipment is shown as mounted on the same base 6 as the recorder. This comprises a pair of insulating brackets 46 which carry a pair of conductors 47 and 48, connected to the filament 49 and grid 51, respectively, of an amplifier 52 which feeds a loudspeaker 53. The form of the conductors is not important as long as their opposed area is small, so that they form a capacity presenting a substantially line surface to the record tape. They may be merely a pair of parallel wires between which the tape is drawn, but I prefer to use rollers of small

diameter as shown, with the upper or grid roller 48 pressed downward against the tape by springs 54.

It is not contemplated that the recording and reproducing systems will usually be used simultaneously, altho this is sometimes done for the purpose of monitoring the record. It is of course apparent that recorder and reproducer can be mounted entirely separately, if desired.

In reproduction the electrized dielectric is drawn between the reproducing electrodes at substantially the same speed as for recording. The electrostatically sensitive vacuum tube relay is affected by the differentially electrified tape within the field of the conductors, and the original impulses are reproduced in its output circuit, to be translated into sound by the loudspeaker.

Practically all incidental or interferent noise can be eliminated in this device. By making the only parts which touch the record before it passes thru the reproducing capacitor of metal, substantially all temporary electrical charges are removed, and these are the chief possible source of interference. When the tape is reeled up, such temporary charges as may have been accumulated are dissipated by the conducting surface of the dielectric.

I claim:

1. The step in the method of recording sound impulses which comprises electrizing a dielectric.
2. The method of recording sound which comprises the translation of the sound into electrical impulses, and electrizing a dielectric therewith.
3. The method of recording sound impulses which comprises electrizing elementary areas of a dielectric in correspondence with the potentials to be recorded.
4. The method of recording sound impulses which comprises establishing an electrostatic field corresponding to said impulses, and causing a molten dielectric to solidify within said field.
5. The method of recording electrical impulses which comprises establishing an electrostatic field corresponding to said impulses, bringing a molten dielectric within said field by a relative motion therebetween, and causing the dielectric to solidify within said field.
6. The method of recording sound impulses which comprises electrizing successive elementary areas of a dielectric in correspondence with the successive impulses to be recorded.
7. A recorder for electrical impulses comprising means for establishing an electrostatic field corresponding to said impulses, means for causing a relative movement between said field and a dielectric, means for melting a portion of the dielectric, and means for causing the solidification of the melted dielectric within the field.

8. A recorder for electrical impulses comprising means for establishing an electrostatic field corresponding to said impulses, means for moving a dielectric thru said field, means for melting a portion of the dielectric, and means for causing the solidification of the melted dielectric within the field.
- 5 9. A recorder for electrical impulses comprising a heater, a cooler adjacent thereto, means for moving a dielectric past said heater and cooler, and means for establishing an electrostatic field thru the dielectric within the field of action of the cooler.
- 10 10. A record of sound impulses comprising an electrified dielectric.
- 15 11. A record of sound impulses comprising a differentially electrified dielectric.
12. A record of sound impulses comprising a paper impregnated with an electrified dielectric.
- 20 13. A record of sound impulses comprising a paper having a conducting surface and impregnated with an electrified dielectric.
- 25 14. The method of reproducing electrical impulses which comprises causing electrified areas of a dielectric successively to actuate an electrically sensitive detector.
- 30 15. The method of reproducing sound which comprises causing successive elementary electrified areas of a dielectric, to actuate an electrically sensitive detector to produce electrical impulses, and translating said impulses into sound.
- 35 16. A phonographic method comprising means for translating the sound into electrical impulses, means for successively electrifying elementary areas of a dielectric with said impulses, and means for reproducing the sound from the record thus formed.
- 40 17. A sound reproducing system comprising an electrified dielectric, a pair of opposed conductors forming a condenser, means for bringing successive elementary areas of the dielectric within the field of the condenser, an electrostatically sensitive detector having an actuating circuit connected to said condenser, and means for utilizing the output of said detector to produce sound.
- 45 18. A recorder for electrical impulses comprising means for moving a dielectric strip, means for heating said strip, means adjacent said heating means for cooling said strip, and a plate insulated from said heating and cooling means positioned to establish an electrostatic field thru said strip in the cooling portion.
- 50 55 19. The method of recording sound which comprises electrifying distributed areas along a dielectric in intensities proportional to the sound impulses.
- 60 In testimony whereof, I have hereunto set my hand.

ROBERT E. RUTHERFORD.
